(57) **CLAIM**

The ornamental design for a file storage cart as shown and described.

DESCRIPTION

FIG. 1 is a front perspective view of a file storage cart, showing my new design;

FIG. 2 is a rear perspective view thereof;

FIG. 3 is a front elevational view thereof, the rear elevational view is identical;

FIG. 4 is a left elevational view thereof, the right side view being a mirror image of FIG. 4;

FIG. 5 is a top plan view thereof;

FIG. 6 is a bottom plan view thereof;

FIG. 7 is a partial enlarged view of FIG. 1;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 2;

FIG. 18 is a partial enlarged view of FIG. 2;

FIG. 19 is a partial enlarged view of FIG. 2; and,

FIG. 20 is a partial enlarged view of FIG. 2.

The broken lines in the figures are for the purposes of illustrating portions of the file storage cart, which form no part of the claimed design.

1 Claim, 12 Drawing Sheets
